FIG. 6

1
RADIALLY CLAMPING GRIPS

BACKGROUND

This invention relates to a gripping or clamping device in which an object such as textile yarn is held angularly about its periphery, but is allowed to move axially through the device. Such clamping devices are found in the so-called open end spinning art, in which devices, yarn is produced by various means for causing unattached fibers to adhere to and form a continuation of the yarn. The invention particularly relates to means for inserting the yarn into the device at the time of start-up or for piecing-up in the event of yarn breakage.

In U.S. Pat. No. 3,372,537 a radially clamping grip of the above type is disclosed. In this patent a cylindrical body is shown having a clamping member which includes a plurality of flexible filaments disposed in a parallel bundle. The object to be gripped is inserted into the bundle so that each filament exerts a force radially upon the object. In order to place the object, such as yarn, into the clamping grip it was necessary to insert a tool of some sort into the bundle so that the filaments were forced apart to enlarge the opening. After the yarn had been drawn through, the tool was removed and the filaments were released into pressing contact with the yarn. The steps required for inserting a yarn into a clamping grip were time consuming and added undesirably to the cost of operation of large numbers of the devices. The present invention provides a clamping grip having the advantages of the flexible filaments, disclosed in the above patent, but permits threading-up by a simple operation requiring considerably less time than before.

SUMMARY OF THE INVENTION

The present invention provides a sliding grip which allows rapid insertion of a yarn or other filiform object to be radially gripped thereby, without using an inserting tool. The clamping grip of the invention has a rotatable body with a semimeridian groove extending from the periphery of the body to an axial hold in which is carried the bundle of flexible filaments. The groove is further provided with a special engagement surface as a simplified means for positioning the yarn prior to its being inserted into the clamping filaments.

It is the general object of this invention to devise a radially clamping grip for filiform objects in which the object may be inserted by a simple operation without using special tools.

BRIEF DESCRIPTION OF THE DRAWINGS

The invention will be described in greater detail by reference to a specific embodiment thereof as shown in the accompanying figures of drawing wherein:

FIG. 1 is a view in front elevation showing the semimeridian groove,

FIGS. 2 and 3 are opposite end views as indicated by arrows II-II and III-III respectively in FIG. 1,

FIG. 4 is a side elevation indicated by arrow IV in FIG. 2,

FIGS. 5a and 5b illustrate, in two views at right angles to one another, the insertion of a length of yarn into the flexible filaments, and

FIG. 6 is a cross section taken on line VI-VI in FIG. 2.

DESCRIPTION OF THE PREFERRED EMBODIMENT

In FIG. 1 is shown a gripping device of the type described, having a cylindrical body 1 with a head 2 at one end and an axially extending through hole 3 terminating at the head end in an inlet funnel 4. The body 1 houses an expandable and contractable clamping member comprising a plurality of flexible filaments regularly arranged around the axis 5 of the hole 3, each of the filaments being arched so as to form a bow-net 6 which encompasses the funnel 4 (FIG. 6). The extension of each flexible filament from the bow-net 6 forms a bundle 7 of filaments coaxial with the hole 3. Between the filaments of the bundle 7 is an axial aperture for the passage of a yarn, held radially by the resilient forces of the flexible filaments, each urged toward the axis 5. Each flexible filament of the plurality

is engaged by a separate one of a series of radially directed slots 8a to 8p (FIG. 3). At least a portion of the arched portion of each filament is positioned in a slot and will be guided thereby during radial displacement as shown in FIG. 6 where slots 8a and 8i retain the arched portions of filaments 9a and 9i respectively.

To facilitate threading-up the device with a prepared yarn the body 1 is formed with a semimeridian groove 10 which provides lateral access to the bundle 7 of the clamping member. As shown in FIGS. 1-4, this arrangement enables a filiform object such as a yarn 11 to be introduced from the side of the body 1 indicated by arrows 12. The yarn 11 may be readily inserted between the arched portions of the filaments 9e and 9h (FIGS. 5a and 5b) which are located on opposite sides of the groove 10. These arched portions are part of the bow-net 6 and therefore diverge more and more as they approach the top of the head 2, so that the yarn 11 can slide between these arched portions into the bundle 7 of the clamping member. Slight tension on the yarn 11 in the direction of the arrow 13 will part the filaments at the point 11a and allow the yarn to enter the bundle 7 and become fully trapped.

The groove 10, whose cross section has the general shape of a sector, is bounded by convex sides 14 and 15 which are symmetrical to one another in relation to the mean plane 16 of the groove and which connect tangentially with the periphery of the body 1, so that the junction ridges 17 and 18 are rounded to the point of vanishing. This provides a smooth entry for the yarn and eliminates the possibility of the yarn catching on any edges of the slot.

In many instances the clamping grip of this invention is used for open end type spinning operations and must be supported for rotation about its axis 5. FIGS. 1-4 show in broken lines a hollow tubular casing 19 into which the body 1 is fitted to be rotated thereby. To insert an end of yarn into the clamping grip, the yarn must be passed through the casing 19 in some manner, for example, by blowing with an air jet. As an aid for this procedure, the body 1 has on either side of the groove 10 yarn engaging surfaces 20 which have the form of a developed or ruled surface whose generatrices are perpendicular to the means plane 16 of the groove 10. The convex sides 14 and 15 of the groove are shaped so that they connect tangentially with the yarn-engaging surfaces 20, causing the junction ridges 21 and 22 to gradually fadeout (FIG. 1).

The removal of material from the body 1 in forming the groove 10 unbalances the clamping grip relative to the axis 5. It is desirable to remove additional material on the side of the body opposite the groove such as at the flat surface 23 (FIGS. 2-3) in order to counterbalance the grip for high speed rotation.

It will be seen that the prime object of the invention has been achieved by providing a sliding, clamping grip which may be threaded-up very simply without the use of special tools and with practically no time loss. Such a grip is highly advantageous for use in spinning frames having large quantities of spinning heads.

The embodiment of the invention in which I claim an exclusive property or privilege is defined as follows:

60 1. A gripping device for resiliently radially clamping the end of a yarn while allowing axial sliding motion of the yarn, said device comprising a rotatable body, an expandable and contractable clamping means contained within said body defining an aperture therethrough, said body having a semimeridian groove extending radially from the periphery of said body providing lateral access to said aperture, and yarn-engaging ruled surfaces in abutting relationship with said groove, the generatrices of said surfaces being perpendicular to the mean plane of said groove.

65 2. A gripping device as set forth in claim 1 wherein said groove is bounded by convex sides which are symmetrical to one another in relation to the means plane of said groove.

70 3. A gripping device as set forth in claim 2 wherein the outlines of said sides connect tangentially with the periphery of said body.

4. A gripping device as set forth in claim 2 wherein the outlines of said sides connect tangentially with said ruled surfaces.

5. A gripping device as set forth in claim 1 wherein said body has a counterbalancing flat surface disposed in diametric opposition to said groove.

Dedication
